UNITED STATES PATENT OFFICE.

JULIUS OMAR FRAZIER, OF NEW ORLEANS, LOUISIANA.

BY-PASSED-FLUE-GAS CANE-JUICE HEATER.

1,311,336.

Specification of Letters Patent. Patented July 29, 1919.

Application filed March 21, 1918. Serial No. 223,878.

To all whom it may concern:

Be it known that I, JULIUS O. FRAZIER, a citizen of the United States, residing at New Orleans, in the parish of Orleans and 5 State of Louisiana, have invented a new and useful By-Passed-Flue-Gas Cane-Juice Heater, of which the following is a specification.

This invention has reference to a heater 10 for cane juice and its object is to utilize by-passed flue gases for heating the cane juice.

In accordance with the invention the main flue for the gases of combustion flowing to the stack is provided with a by-pass and in 15 the main flue there is located a damper by means of which the gases of combustion may travel directly through the flue to the stack or may be diverted through the by-pass, and such action may be brought about automatically. 20

Located in the by-pass is a series of connected ducts or pipes to present a long tortuous passage for the cane juice so that the heated gases of combustion may act thereupon for a desirable length of time, and in order to increase the effect and supplement furnace draft the by-pass is provided with draft producing means such as a fan. The cane juice is forced through the tortuous 25 passage by any suitable power means and provision is made whereby, should the flow of cane juice be stopped for any reason, the course of the flue gases is so controlled that such gases will pass directly through the flue 30 to the stack instead of through the by-pass, whereby overheating of the cane juice is avoided. Furthermore, provision is also made for ready access to the pipes through which the juice flows for cleansing and other 35 purposes and provision is made for ready access to the exterior of the pipes whereby deposits of soot and the like thereon may be removed without dismantling the structure. 40

The invention will be best understood 45 from a consideration of the following detailed description taken in connection with the accompanying drawings forming part of this specification, with the understanding, however, that while the drawings show a 50 practical form of the invention, the latter is not confined to any strict conformity with

the showing of the drawings but may be changed and modified so long as such changes and modifications come within the scope of the appended claims. 55

In the drawings

Figure 1 is an elevation, with some parts broken away and in section, of a cane juice heater embodying the invention;

Fig. 2 is a section on the line 2-2 of Fig. 60 1 but drawn on a larger scale and showing portions of the headers on the top of the figure in plan view;

Fig. 3 is a section on the line 3-3 of Fig. 65 1 but drawn on the scale of Fig. 2;

Fig. 4 is a detailed sectional view of a 70 damper controller used in connection with other features of the invention.

Referring to the drawings there is shown a flue 1 which may be taken as indicative of 75 a flue for the gases of combustion, leading from a furnace to a stack but neither the furnace nor the stack is shown in the drawings. At spaced points there are branch flues 2 and 3 respectively, each connected 80 with main flue 1 and in turn connected together, in a manner to be described, at the ends remote from their connections with the main flue.

Each branch flue 2 and 3 at the end remote 85 from its connection with the main flue 1 has an extended mouth 4 and at opposite portions, say the top and bottom, are connecting plates 5 and 6 respectively, secured to the branch flues 2 and 3 by rivets 7 or 90 in any other appropriate manner.

Considering the plates 5 and 6 as the upper and lower parts of the connections 95 between the mouths 4 of the branch flues 2 and 3, the two sides of the parts connecting said branch flues are made up of a series of frames 8 each having one edge 9 overlapped by the other edge 10 of a neighboring frame and these overlapping portions are secured together by rivets 11 or otherwise. The connected frames 8 are on opposite sides of a duct 12 extending between the two branch flues 2 and 3 so that the gases of combustion, when properly diverted, pass through the flue 2, to and through the duct or flue 12 and 100 out through the flue 3 to the flue 1 or to the atmosphere. The frames 8 carry headers

13 alternating on opposite sides of the flue 12, with the terminal headers having sections 13^a, and together with the frames 8 forming the side walls of the flue 12. The 5 headers are connected by tubes 14 which may be arranged in pairs or otherwise to increase the area of flow from header to header. Each group of tubes forms a separate path or pass for the liquid, for the purpose of 10 increasing the heating surface per unit of pass length for a given volume of moving liquor. This also provides a better division of the hot gases among the smaller or thinner volumes of liquor and reduces the distance of the most remote liquor, that at the 15 center of the tube, from the heating surface. In the particular arrangement shown in Fig. 1, there are six sections including twelve headers, the headers being connected together at opposite ends in series by pipes 15. The entrance of the liquor is by way of an 20 inlet pipe 16 at that end of the series where the cooler gases are discharging, the exit of liquor being at an outlet 17 where the hot- 25 est gases are entering the heater, thus preserving the best available balance of temperature difference.

At the right hand section of Fig. 1 the 30 interior of the return chambers are exposed showing eight four-tube groups to each section. The liquor entering at 16, Fig. 1, makes eight transits across the flue 12 in that section and the same occurs in each 35 succeeding section, emerging at 17 to the right. The division of a given volume into four streams as against one of equal area, doubles the heating surface in any unit, maintains the primary velocity with but slightly increased friction and reduces the 40 distance by half of the liquor most remote from the tube walls. The inlet pipe 16 is connected to a pump 18 or other means for causing flow of the cane juice, or other liquid into and through the apparatus, and between 45 the pump 18 and the pipe 16 is a damper controller 19 which in the particular arrangement shown is provided with an interior plate or pendulum disk 20 preferably of oblong or elliptical form. This disk is movable between the inlet and outlet sides of the 50 damper controller and is of a size that it does not obstruct the flow of cane juice. The interior of the damper controller 19 is provided with stops 21 limiting the movement 55 of the disk 20. The disk 20 is carried by a rock shaft 22 having rock arms 23 and 23^a outside of the casing. The arm 23 is provided with an adjustable counterweight 24.

The other arm 23^a has attached to it one 60 end of a rod 25, the other end of the rod being attached to a rock arm 26 on one end of a rock shaft 27, extending through the flue 1 and within the latter carrying a valve or damper 28 in the path of which are stops 65 29, whereby in one position of the disk 20

the damper 28 is fully open and in the other position of the disk 20 is closed against the stops 29.

Within the end 3 of the by-pass flue is a fan 30 mounted on the shaft 31 extending 70 through a housing 32 opening through the walls of the end 3 of the by-pass to a point where it may receive power from any suitable source, preferably though not necessarily a variable speed electric motor. 75

Each header 13 and 13^a is provided with removable chamber covers 34, each cover or plate covering two adjacent liquor passages, whereby access may be had to the heating tubes 14. These covers or cap plates are 80 held to the respective headers each by a clamp or clamps 35 traversed by set screws 36, the clamps having hook ends 37 engaging behind extensions 38 of the respective header. The covers and clamps are all alike and 85 therefore interchangeable.

The plates 8 between the headers are pierced by passages 39 normally closed by plugs 40 so that on the removal of the plugs 90 the exteriors of the tubes 14 may be cleansed from deposits of soot and the like from the gases traversing the duct or chamber 12 in which these tubes are located.

With the heater described the cane juice is directed through the pipe 16 from the 95 pump 18, passing by way of the casing 19. The course of the cane juice through the tubular heater made up of sections each comprising headers and connecting tubes, is a tortuous one with the flow of juice back and 100 forth across the flow of hot gases of combustion diverted from the main flue through the by-pass flue in which the tubular sections are installed. The rapidity of flow of the 105 gases of combustion through the by-pass is increased by use of the fan 30 and the area of juice flow passages is so proportioned that the juice may have a velocity of say 550 ft. per minute, which velocity has been found most effective against deposits on the 110 inner tube surfaces.

Provision is made for access to the tubes both inside and out with the tubes straight so that their inner surfaces may be readily reached and cleaned mechanically, should it 115 become necessary, while a steam blast may be employed for cleaning the outer or fire sides of the tubes.

The by-pass arrangement is especially adapted for utilizing hitherto waste heat of 120 furnace gases on their way to the stack.

In order to prevent undue concentration of the juice and the possible ruinous scorching of the same, should there be any cessation of the flow of the juice, the automatic 125 control of the damper in the main flue is provided. When there is no flow of liquid into the heater the swinging disk 20 is against the stop 21 toward the pump 18, with the result that the damper 28 is open, 130

this being brought about by the weight 24. When the juice or liquor enters the casing 19 the disk 20 is swung by the force of the current against the stop 21^a toward the group 5 of tubes 14 whereby the damper 28 is closed. The juice or liquor follows a tortuous course through the by-pass where it is subjected to the action of the hot gases of combustion. This continues until, for some reason, the 10 flow of juice ceases, whereupon the weight 24 automatically swings the disk 20 and at the same time opens the damper 28.

By making the heater of sectional construction with each section separate from the 15 others, it is possible to increase the heating area by adding sections as may be found advisable.

The tubes and the headers they connect are grouped into units which in the particular 20 showing of the drawing are narrow in the direction of the length of the by-pass and occupy a space corresponding to the cross sectional area of the by-pass. This permits the assemblage of as many units as may be desired 25 in the direction of the length of the by-pass, so that the by-pass may be made longer or shorter by adding or subtracting units from the assemblage. This makes the arrangement quite flexible with respect to 30 its capacity and for meeting various conditions.

In the particular showing of the drawings the pipes 14 are arranged horizontally, but it will be understood that the pipes may be 35 arranged vertically and the headers instead of being placed at the sides of the by-pass may be located at the top and bottom thereof.

The invention is applicable for heating 40 both cane juice and beet juice from which sugar is ultimately produced and the invention may be utilized for heating other liquids.

The by-pass very satisfactorily solves the 45 problem of utilizing waste heat, because the heat utilizing installation in the by-pass in no wise interferes with the normal furnace operation. This is due to the fact that the flue gases may be directed wholly through 50 the unobstructed main flue or wholly through the by-pass, in which by-pass the entire heat utilizing means are located.

What is claimed is:—

1. In a heater for the purpose described, 55 the combination with a flue for conducting gases of combustion, of a by-pass connected to the flue, a series of pipes located in and extending back and forth through the by-pass for conducting liquid, a damper within 60 the flue between the ends of the by-pass, and a valve connected to the pipes and responsive to liquid pressure, said valve having a normal tendency to close the damper in the flue.

65 2. In a heater for the purpose described

and designed to utilize flue gases, a by-pass connected to the flue, a series of separate units consisting of headers and connecting pipes with the units connected in series and all lodged in and forming part of the by- 70 pass structure, a valve connected to the entering end of the series of units and responsive to the flow of liquid to the pipes, and means under the control of the valve for causing the products of combustion to flow 75 through the by-pass to heat the units or to be diverted therefrom.

3. In a heater for the purpose described, the combination with a flue for conducting gases of combustion, of a by-pass for the 80 gases of combustion connected to the flue, means for directing fluid through the by-pass for subjection to the action of the products of combustion, a damper within the flue between the ends of the by-pass, and 85 a valve responsive to the pressure of the fluid to be acted upon in the by-pass and having a normal tendency to close the damper in the flue.

4. A heater for liquids utilizing hot 90 products of combustion as the heating agent, comprising a flue, a damper therein, and a by-pass around the damper with the body of the by-pass composed solely of a series of units connected face to face in order, 95 each unit consisting of headers and pipes joining them for the serial travel of liquid through them and the headers constituting walls of the by-pass.

5. A heater for liquids utilizing hot 100 products of combustion as the heating agent, comprising a by-pass through which the hot products of combustion may be diverted, said by-pass including a plurality of units 105 each composed of headers and pipes spacing them and joining them in series, and each unit having means joining it to the next unit in order, pipes joining the units together in series, and plates bridging the spaces between the header ends of the units, to thereby define the body portion of the by-pass. 110

6. A heater for liquids utilizing hot 115 products of combustion as the heating agent, comprising a by-pass through which the hot products of combustion may be diverted, said by-pass including a plurality of units 120 each composed of headers with removable cap plates, straight pipes connecting the headers of each unit in series and spacing the headers of the unit apart, said headers having means joining them to the next unit in order, pipes joining the units together in series, and plates bridging the spaces between the header ends of the units, to thereby define the body portion of the by-pass. 125

7. A heater for liquids utilizing hot products of combustion as the heating agent, comprising a by-pass through which the hot products of combustion may be diverted, said by-pass including a plurality of units 130

- each composed of headers with removable cap plates, straight pipes connecting the headers of each unit in series and spacing the headers of the unit apart, said headers having means joining them to the next unit in order, pipes joining the units together in series, and plates bridging the spaces between the header ends of the units, to thereby define the body portion of the by-pass, said end plates also being provided with normally closed passages for permitting access to the exteriors of the pipes. 10
8. In a heater for the purpose described, the combination with a flue for conducting gases of combustion, of a by-pass structure connected with the flue and consisting of a series of units each composed of headers and pipes connecting the headers and arranged in serial order, the headers having matching means at adjacent sides connected together to constitute the corresponding side walls of the by-pass, and plates connected to the headers to form the remaining walls of the by-pass. 15
- 25 9. In a heater for the purpose described, a flue for gases of combustion, and a by-pass for the flue comprising end members respectively connected to the flue at separated points, and a series of units constituting the body of the flue and connected by the end members to the flue, each unit comprising headers and pipes connecting them in serial order and each header being connected to the next header in order at the same side of the body of the by-pass to constitute walls for the body of the by-pass, and plates connecting the ends of the headers to constitute the remaining walls of the by-pass. 30
- 35
10. In a heater for the purpose described and designed to use flue gases, a by-pass connected to the flue, a liquid circulating system in the by-pass, a damper in the flue between the ends of the by-pass, and a valve included in the circulating system and responsive to move toward the open position under pressure of the liquid flowing through the circulating system, said valve having a normal tendency to close and thereby open the damper in the flue. 40
11. In a heater for the purpose described, a flue for gases of combustion, and a by-pass for the flue comprising end members, and a series of units constituting the body of the flue, each unit comprising headers and groups of pipes with the pipes of each group in multiple, and each header being connected to the next header in order at the same side of the body of the by-pass to constitute walls for said body of the by-pass, and plates connecting the ends of the headers to constitute the remaining walls of the by-pass. 45
12. In a heater for the purpose described and designed to use flue gases, a by-pass for the flue gases, and a liquid circulating system in the by-pass including a series of headers and groups of pipes in multiple connecting the headers with the headers connected serially, and said headers constituting portions of the walls of the by-pass. 50
- 55
- 60
- 65
- 70
- In testimony, that I claim the foregoing as my own, I have hereto affixed my signature in the presence of two witnesses.
